UNITED STATES PATENT OFFICE.

GEORGE HOWLETT DAVIS, OF NEW YORK, N. Y.

ELECTRIC SELF-PLAYING PIANO.

SPECIFICATION forming part of Letters Patent No. 719,092, dated January 27, 1903.

Application filed March 22, 1899. Serial No. 710,046. (No model.)

To all whom it may concern:

Be it known that I, GEORGE HOWLETT DAVIS, a citizen of the United States, residing at New York, in the county of New York and State of New York, have invented a certain new, useful, and valuable Improvement in Electrical Self-Playing Pianos, of which the following is a full, clear, and exact description.

10 This invention relates to electrical self-playing pianos and similar musical instruments, and is in the nature of an improvement on the instruments for which I obtained Letters Patent of the United States on the 15 17th day of September, 1895; and November 10, 1896, and respectively numbered 546,582 and 570,911.

The object of the present invention is to improve, simplify, and cheapen the construction of many of the details of construction of the parts of the instruments shown and described in said Letters Patent and to improve and render certain and satisfactory their operation, and in certain other features, as will 25 fully hereinafter appear.

To these ends my invention consists in the features and in the construction, combination, and arrangement of parts hereinafter fully described, and particularly pointed out 30 in the claims following the description, reference being had to the accompanying drawings, forming a part of this specification, wherein—

Figure 1 is a view in end elevation, partially in section, showing my improved device applied to a piano. Fig. 2 is a bottom plan view of the music-roll holder. Fig. 3 is an end elevation, partially in section, of the same. Fig. 4 is a detail view of the rewinding spring-drum. Fig. 5 is a detail perspective view of the contacts and their guard-rail viewed from the under side. Fig. 6 is a similar view of the switch-rail. Fig. 7 is a detail view of the music-roll-holder-releasing mechanism. Figs. 8 and 9 are detail views of the brake for regulating or governing the rotation of the take-up roll. Fig. 10 is a detail perspective view of one of the armature-supporting springs, and Fig. 11 is a diagrammatic view illustrating the circuits.

Referring to the drawings, the numeral 1 indicates an electric motor arranged in the

bottom of the piano and operating to drive a belt 2, which passes around a pulley 3, fixed on one end of a drum 4. The ends or trunnions 5 of the drum are journaled in suitable bearings formed in metallic hangers or brackets 6, pendent from the under side of the piano-frame beneath the inner ends of the piano-keys 7. The hangers 6 are rigidly united 55 by angle irons or bars 8 and 9, which taken together constitute a frame which carries or supports all the parts forming the action for operating the piano-keys, as contradistinguished from the music-sheet holder. This 60 frame may be quickly attached to the piano-frame by ordinary wood-screws without altering or injuring the piano-frame in any manner whatsoever. Supported on the angle-bar 8 is a series of electromagnets 10 65 equal in number to the number of piano-keys. The horizontal web of the angle-bar is provided with a number of perforations, two for each magnet, and the U-shaped core or poles of the magnets are passed up through the 70 perforations and soldered to the web, after which the helices are placed over the poles above the web. This manner of arranging the electromagnets forms a very economical, 75 secure, and compact support therefor. Riveted, bolted, or otherwise suitably secured to the vertical flange of the angle-bar are a number of flat springs 11, one for each magnet, 80 which are bent at right angles at their upper ends to overlie the upper ends of the magnets, and to each of said springs is rigidly attached a bent or approximately right-angled armature 12, one end 13 of which depends vertically, as shown. To the lower end of the 85 pendent arm 13 of each of the armatures is pivoted a shoe 14, the lower edge of which is preferably slightly curved or convexed, as at 15, and normally lies slightly above the revolving drum 4. As shown, the armature is pivoted to one corner of the upper end of the shoe, while to the opposite corner thereof is in like manner attached a vertically-movable striker-rod 16, arranged to slide in suitable bearings of any suitable description and adapted to engage or strike the 90 under side of the inner end of the piano-key 7, lying immediately above it. Rigidly fixed in the angle-bar 9 are a number of downwardly-projecting rods 18, which operate to

limit the upward movement of the armatures 12. As best shown in Fig. 10, the flat springs 11 are made vertically adjustable by providing each with an elongated slot 17, through 5 which the attaching-bolts pass, and the vertical portion of each of said springs is bent up at right angles on its opposite edges, as shown, to form strengthening ribs or flanges.

It will be readily understood by those 10 skilled in the art that if one of the magnets 10 be energized its armature 12 will be attracted and drawn downward, thus forcing the lower edge of the shoe 14 into contact with the drum 4, which constantly revolves 15 in the direction of the arrow 19, whereupon the shoe will instantly be swung upwardly about its pivotal connection to the armature as a center, thrusting upward the striker-rod 16, which in turn strikes its corresponding 20 key and sounds a note. The purpose of supporting the armatures on flat springs, as shown, instead of pivoting them, as has heretofore been customary, is to avoid the noise heretofore found to be occasioned by the piv- 25 oted armatures, for although the noise of a single armature oscillating about its pivot is but slight, yet in practice it is found that the large number of armatures, many of them operating simultaneously, and the rapidity with 30 which they are actuated combine to create sufficient noise to interfere with the proper action of the piano and occasion annoyance. By suspending the armatures on springs, as shown, this objection is entirely avoided.

35 The means for automatically energizing and demagnetizing the electromagnets in proper order and timed intervals to cause the striker-rod to actuate the keys of the piano will now be described.

40 The numeral 20 indicates the base or bottom frame of the music-sheet holder, which is provided at its rear end with tenons 21, which are inserted in suitable circular recesses or sockets formed in the frame of the 45 piano and may be further secured in place by ordinary wood-screws. The forward ends of the base or bottom frame have formed therein bearings 22 and 23, in the former of which is journaled a short shaft 24 and in the 50 latter is loosely arranged a screw 25. Hinged on the shaft 24 and screw 25 is the movable member of the music-sheet holder, consisting of the frame 26, in the rear ends of which is journaled the take-up roll 27, upon which the 55 music-sheet is to be wound to play the piano, as will hereinafter be explained. The take-up roll is provided at one end with a gear-wheel 28, which is adapted to mesh with a small pinion 29, fixed on one end of a cone- 60 pulley 30, which is journaled in a bearing 31, formed on the bottom frame of the sheet-holder. The cone-pulley is driven by a belt 130, which passes around a similar cone-pulley 131, fixed on a shaft 132, journaled in the 65 bracket 6 and also having fixed thereon a belt-pulley 133, which is driven by a belt 134, connected to the pulley 3 before described.

The cone-pulley 30 through the medium of the pinion 29 and gear-wheel 28 drives the take-up roll to advance the music-sheet. 70 Loosely journaled in the frame 26, intermediate the ends of the latter, is a copper-faced contact-roller 32. Journaled in one side of the front portion of the frame 26 is a short shaft 33, the inner end of which is furcated, 75 as at 34, (see Fig. 2,) and on its outer end is fixed a pinion 35, that meshes with a relatively large gear-wheel 36, journaled on a stud-shaft fixed in or formed on the frame 26, which in turn meshes with an idle gear-wheel 80 37, that gears with a similar gear-wheel 137, fixed on the short shaft 24. Formed in the other side of the frame 26 in alignment with the furcated shaft 33 is a bearing 38, in which is adapted to be journaled one end of the delivery-roll 39, the other end of which is adapted to be fixed in the split or furcated end 34 of said shaft 33. The perforated music-sheet is wound on the roll 39 and from thence passes over the contact-roll 32, and at its end is provided with a perforation that is slipped over a hook 40 on the take-up roll. It will be manifest that as the latter is rotated in the direction of the arrow, Fig. 1, the music-sheet 41 will be wound up on the take-up roll 95 and simultaneously unwound from the delivery-roll, passing over and rotating the contact-roll 32. It will be evident that in unwinding the music-sheet from the take-up roll when the end of the music-sheet is reached 100 the perforated end will slip from off the hook 40 and the music-sheet be thus automatically cast off.

Arranged to rest on the periphery of the contact-roller 32, or, more properly speaking, 105 on the music-sheet at the point where it passes over the contact-roller, is a series of contacts or brushes 42, there being one such contact or brush for each key of the instrument to be played upon. Each brush or contact 42 preferably consists of three copper wires arranged in bunches or brush form, the wires of each bunch or brush 42 being collected and inserted at one end in a wooden bar or rail 43, and at its inserted end soldered or otherwise electrically connected to one end of a wire conductor 44, the other end of said conductor being threaded through a perforated switch-rail 45, secured to the frame 20 by screws, as shown, and looped about itself and then bent 110 back over the edge of the rail 45, as at 46, as best illustrated in Fig. 6 of the drawings. It will be understood that each brush or contact 42 is connected in the manner described by a wire conductor 44 to the switch-rail 45, and 115 that by looping the ends of the conductors 44 about the switch-rail in the manner described said loops form broad contact-surfaces that insure a closed and certain electrical contact with the conductors leading to the electromagnets 10, as will more fully hereinafter be made apparent. The bar or rail 43 is fixed to the front side of a metallic bar 47 by screws 48, as most plainly shown in Fig. 3, and on 120 125 130 135

the ends of the bar 47 are formed forwardly-projecting ears or extensions 49, each provided with elongated slots 50. The bar 47 is adjustably secured to the base-frame of the 5 music-roll holder by screws 51. (See Fig. 2.) By loosening the screws 51 the bar 47, and with it the brushes or contacts, may be moved toward or from the contact-roller 32, whereby as the ends of the brushes or contacts wear 10 away they may be adjusted up to the contact-roller to compensate for such wear.

As shown and described, the rails 43 and 45 are removably attached to the frame 20, and this is important, for in practice the conductors 44 may be assembled and secured in place 15 on the rails before the latter are attached to the frame 20, thus rendering the operation of wiring simple, easy, and convenient, after which the whole series of wires may be assembled 20 in place at one operation by merely securing the rails 43 and 45 in place.

Heretofore it has been found in practice that the slender copper wires forming the brushes or contacts 42 are constantly being 25 bent, deflected, or disarranged from one cause or another in such manner that they fail to make proper electrical contact with the contact-roller 32 when it is their duty to do so, and in order to protect and guard the free 30 ends of the said contacts or brushes and at all times maintain them in alinement with one another I provide the following means: Disposed longitudinally over the free ends of the contacts 42, and consequently over 35 the contact-roller 32, is a bar 52, preferably formed of wood, said bar or rail being attached at its opposite ends by screws 53 to the free ends of springs 54, said springs at their other ends being fixed to the base-frame 40 20 of the music-roll holder. The forward edge of the bar or rail 52 is formed with a depending flange 55, and the springs 54, when the contact-roller is not in operative position, force said bar or rail down against the free 45 end of the contacts or brushes, the flange 55 overlapping their extremities, thus protecting said brushes or contacts against being accidentally bent or deflected from their true positions. When the frame 26 is swung up 50 into position to cause the contact-roller 32 to bear against the free ends of the contacts or brushes 42, as will hereinafter be described, the sides of said frame abut the screws 53 of the guard-rail 52 and raise the latter out of 55 engagement with the contacts or brushes. Secured at one end to the frame 26 by a screw 56 is a spring-contact 57, which at its free end constantly bears against one end of the contact-roller 32, thus placing said roller 60 in electrical contact with said frame.

As before described, the music-roll-holder frame 26 is hinged at its front end, as at 24 and 25, to the base-frame 20, and said music-roll-holder frame is held in its raised position 65 by depending beveled catches or hooks 58, that are adapted to hook under projections 59, formed on the opposite sides of the frame

26. Said catches or hooks 58 are formed on and depend from the opposite ends of a bar 60 and are each pivoted intermediate their 70 ends on screws 61, screwed into the sides of the frame 20. Arranged to move longitudinally in bearings 62, formed on the frame 20 and transversely to the bar 60, is a rod 63, which intermediate its ends is provided with 75 a depending pin 64, which engages a perforation in the bar 60. About the rod 63 is coiled a spring 65, one end of which bears against the rearmost bearing 62 and the other end against the pin 66, fixed in or on said rod. 80 Said spring operates to thrust the rod 63 forward, and thus hold the catches 58 in engagement with the projections 59, thereby maintaining the frame 26 in its raised position. The forward end of the rod 63 is provided 85 with the knob 67, by means of which the rod may be thrust rearwardly to disengage the catches and drop the frame 26, for the purpose hereinafter explained. Fixed on the rod 63 is an armature 68, which normally de- 90 pends in front of the electromagnet 69, which is connected by a wire 70 to a contact 71, adapted to contact with the contact-roller 32, the other conductor 72 terminating in a loop 73 on the switch-rail 45. Formed on one side of 95 the base-frame 20 is a horizontally-extending plate or flat projection 74, on the lower side of which is secured a sheet of insulating material 76. Threaded through suitable perforations in the insulating sheet or plate 76 is a 100 resistance-coil 77, one end of which is soldered or otherwise electrically connected to the plate or projection 74, as diagrammatically shown in Fig. 11, and hence is in electrical connection with the frame 20. A sheet of insulating material (not shown) is arranged between the sheet or plate 76 and the convolutions of the resistance-coil and the plate 74 to insulate said coil from the last-named plate. 105

As shown most clearly in Fig. 2, the convolutions of the rheostat or resistance-coil 77 are arranged in the arc of a circle, and adapted to sweep over said coil is a switch-lever or pivoted arm 78, which is pivoted at one end 110 to the insulating-plates 75 and 76 and at its other end is provided with a contact 79, adapted to make electrical contact with any one of the convolutions of the resistance-coil 77. The arm or lever 78 is connected to one 115 end of a wire conductor 80, the other end of which terminates in a loop 81 on the switch-rail 45. Pivoted to the plate 74 and in electrical contact therewith, and hence also in electrical contact with the frame 20, is a 120 switch-lever 82, which normally rests in electrical contact with a switch-bar 83, secured to the insulating-plate 76. An inclined shoulder 84 is formed on the edge of the plate 74, upon which the switch-lever 82 is adapted to 125 ride when turned in the proper direction, and thus be thrown out of electrical contact with the switch-bar 83. To the opposite end of the switch-lever 82 is attached an up- 130

wardly-projecting U-shaped belt-shifting arm 85, as most clearly shown in Figs. 1 and 2, which embraces the opposite sides of the belt 130, connecting the cone-pulleys 30 and 131, the operation of which will herein-after be explained.

Fixed to the base-frame 20 and suitably insulated from one another are two sprung-contacts 86, one of which is connected by wire 10 conductor 87 to the switch-bar 83, and the other is connected to a similar conductor 88, that terminates in a loop 89 on the switch-rail 45. On the forward end of the movable part 26 of the music-sheet holder is fixed a 15 metallic pin or projection 90, which when the music-roll holder is swung up into position enters between and engages both the sprung-contacts 86 and places the conductors 87 and 88 in electrical contact.

20 Fixed to the upper ends of the brackets 6 is a bar 91, of insulating material, preferably wood, to which are secured by screws 92 spring-contacts 93, there being one such contact for each of the brushes 42 and its corresponding conductor 44. Similar spring-contacts 172, 181, and 189 are also secured to the bar 91. When the music-roll holder and its base-frame are inserted in place, the sprung-contacts 93 each automatically makes electrical contact with one of the loops 46, forming the terminals of the conductors 44, connected with the brushes, and in like manner the contact 172 is placed in electrical contact with the conductor 72, leading to the armature 35 controlling the catches operating to hold the music-roll holder elevated. The contact 181 is placed in electrical contact with the conductor 80, leading to the rheostat, and the conductor 189 in contact with the conductor 88, 40 leading through the frame of the music-roll holder, and conductor 87 to the switch-bar.

The numeral 95 indicates a battery or other suitable source of electricity one terminal 96 of which passes through the motor 1 and from 45 thence to the contact 181, while the other terminal 97 leads from the contact 189 back to the battery. A number of conductors 98 also lead from the conductor 96, each passing through one of the electromagnets 10 and 50 thence to one of the contacts 93. A third conductor 99 leads from the conductor 96 to the contact 172.

The operation of the invention so far as described is as follows: The electric current 55 passes from the generator 95 over the conductor 96, through the motor 1, thence over conductor 80, through the rheostat 77 to the switch-lever 82, through the conductor 87, contacts 86, and connector 90, conductor 88, 60 and thence back to the generator over conductor 97, thus putting the motor into operation. The motor drives the shaft 4 in the direction shown by the arrow. Assuming that a perforated music-sheet has been properly 65 placed in the music-roll holder, the take-up roller 27, through the medium of the cone-pulleys 30 and 131 and belts 130 and 134, will

unwind the sheet from the delivery-roller 39, drawing it over the contact-roller 32. As a perforated portion of the music-sheet passes 70 beneath any one of the brushes or contacts 42 the free end of the latter will make electrical contact with the contact-roller 32. The circuit will then be completed from the generator over the conductor 96 98, through an 75 electromagnet 10, conductor 44, the brush 42, contact-roller 32, frame 26, conductor 88, and back over the conductor 97 to the generator. The electromagnet 10 will thus be energized, drawing down its armature 12 and throwing 80 the shoe 14 into frictional contact with the rotating drum 4, which will immediately operate to swing said shoe up about its pivotal point, thus thrusting up the striker-rod 16 and actuating the corresponding key 17 to 85 sound a note. When the music-sheet moves forward to again interpose itself between the end of the brush and the contact-roller, the circuit will be broken at such point, demagnetizing the magnet and restoring the parts 90 to their former positions. As before stated, there is one such brush, magnet, and circuit for each key of the instrument, and they will be each operated at such times to sound the note as may be determined by the perforations 95 in the music-sheet in the manner well understood by those skilled in the art. When the end of the music-sheet is reached, an appropriately-placed perforation therein will come opposite the contact 71, whereupon a circuit 100 will immediately be completed from the generator over the conductor 99, conductor 72, through the electromagnet 69, conductor 70, contact 71, contact-roller 32, frame 26, conductor 88, and thence back over the conductor 105 97 to the generator. The electromagnet 69 will be thus energized, retracting the rod 63 and disengaging the catches 58 from the projections 59, whereupon the frame 26 will immediately swing down by gravity, withdrawing 110 the pin or projection 90 from between the contact 86, breaking the circuit at this point and throwing the motor out of operation.

It will be evident that by turning the pivoted arm 78 to the right or left more or less 115 of the convolutions of the coil 77 will be thrown into the motor-circuit, thereby altering the resistance, and consequently regulating the speed of the motor. As the force with which the striker-rods are thrust upward 120 against the keys depends to some extent upon the rapidity with which the drum 4 revolves, (the faster the rotation of the drum the more forcibly said rods being thrust upward, and consequently the louder the notes,) the volume of the sound of the instrument may in a 125 measure be controlled by regulating the speed of the motor by means of the rheostat.

In order that the tempo or rapidity with which the notes are sounded may be rendered 130 independent of the rapidity with which the motor is driven, I have provided the arrangement of cone-pulleys and belt-shifter described. It will be readily understood that

by turning the switch-lever 82 in one direction or the other the belt 130 will be shifted on the cone-pulleys by the shifter-arm 85 to cause the music-sheet to be moved faster or 5 slower independently of the speed of the motor, and hence regulate the rapidity with which the key-actuating circuits are closed. This movement of the switch-lever 82 does not affect the motor, as said switch-lever makes 10 contact with the switch-bar 83 at any point to which it may be moved to shift the belt, and it is only when the switch-lever is forced so far to one side as to ride up on the inclined shoulder 84 that it is moved out of contact 15 with the switch-bar and breaks the motor-circuit. The switch-lever thus performs a two-fold function. It controls through the medium of the belt shifter-arm 85 the speed at which the music-sheet travels and also operates to throw the motor into and out of operation.

There now remains only to be described the mechanism for rewinding the music-sheet after it has been unwound from the delivery-roll onto the take-up roll.

Depending from the rear end of the base-frame 20 is a bracket-arm 100, in which is fixed a shaft 101. A sleeve 102 has a loose bearing on the shaft 101, and rotatably arranged on said sleeve is a drum 103, in which is arranged a convolute spring 104, one end of which is fixed, as at 105, to the drum and the other end to the sleeve 102. On the inner or rear end of the sleeve is fixed a ratchet-wheel 106, which is engaged by a pawl 107, pivoted to the bracket-arm and operating to prevent the sleeve from rotating in one direction. One edge of the periphery of the drum 103 is toothed, as at 108, and meshes with a pinion 109, fixed on one end of the shaft 110, journaled in suitable bearings on one side of the frame 20. On the opposite or front end of the shaft 110 is fixed a beveled pinion 111, that meshes with a corresponding beveled pinion 112, fixed on the short shaft 24, before mentioned. The delivery-roll 36 being fixed in the bifurcated end of the shaft 34, it is manifest that said shaft is rotated as the music-sheet is unwound from the delivery-roll 50 onto the take-up roll and through the medium of the gears 35, 36, 37, and 137 rotates the short shaft 24. The latter rotates the shaft 110, which in its turn rotates the drum 103 and winds up the spring 104, the pawl 107 holding the sleeve 102 against rotation, thus storing up power to rewind the music-sheet. When the end of the music-sheet is reached and the music-roll-holder frame is dropped down in the manner before described, thus 55 throwing the gear-wheel 28 on the take-up roller out of gear with the pinion 29 on the cone-pulley 30, the drum is instantly rotated by its spring in the reverse direction to that before described and through the described 60 intermediate gearing immediately rotates the delivery-roller to rewind thereon the music-sheet, which slips off the hook 40 when its

end is reached. When the drum is unwound under the influence of its spring, the pawl slips idly over the ratchet 106, permitting the sleeve 102 to rotate with it, thus preventing the acquired momentum of the drum from expanding or unwinding the spring too far, which would have a tendency to break it. The music-roll may then be removed and another substituted, when it is merely necessary to lift or swing the music-roll-holder frame up into place, when the circuit is again established through the contact 86 and, if the switch be closed, starts the instrument again 80 playing. There being no tension on the take-up roll when the music-roll-holder frame is dropped or swung down, as described, the spring-drum will manifestly operate to wind up the music-sheet on the delivery-roll very 85 quickly, and in order to retard such action and prevent damage to the music-sheet I provide the take-up roll 27 with a centrifugal brake mechanism. (Best illustrated in Figs. 8 and 9 of the drawings.) Referring to said 90 figures, the numeral 113 indicates a cap arranged opposite one end of the take-up roller 27 and fixed in any suitable manner against rotation. In the present instance the cap 113 is shown as being fitted over a boss 114, 95 formed on the inner face of one of the sides of the frame 26, through which passes the journal pin or screw 115, on which the adjacent end of the take-up roller is journaled. Driven in said end of the take-up roller are 100 pins 116, on which are pivoted cam-shaped brake-shoes 117, which when the take-up roller is rotated too fast by the delivery-roller as the latter is actuated by the spring-drum to rewind the music-sheet are thrown 105 outward against the rim of the cap 113 by centrifugal force and operate to retard the movement of the rewinding mechanism. Springs 118 are attached at one end to the free 110 ends of the brake-shoes 117 and at their other ends two pins 119 in the ends of the take-up roller and normally operate to hold the brake-shoes out of contact with the cap 113. By retarding the rotation of the take-up roll in the manner described not only is liability of 115 damage to the music-sheet avoided, but the latter is also caused to be rewound tightly and uniformly on the delivery-roll, which is very important to insure the proper operation of the playing mechanism.

Having described my invention, what I claim is—

1. In a rewinding device for music-roll holders for self-playing instruments, the combination with a delivery-roll and take-up roll, 125 means for driving the take-up roll, and means for disconnecting the driving mechanism from the take-up roll to permit the latter to run free, of a spring-drum and intermediate gearing operating to transmit rotary movement from the delivery-roll to the drum to wind up the spring, the arrangement being such that as the music-sheet is unwound from the delivery-roll the spring is wound up and 130

operates, when the driving mechanism is disconnected from the take-up roll to rewind the music-sheet on the delivery-roll, substantially as described.

5. 2. In a rewinding device for music-roll holders for self-playing instruments, the combination with a delivery-roll, of a sleeve loosely journaled on a support and having fixed thereon a ratchet-wheel, a pawl engaging said ratchet-wheel and operating to prevent the sleeve from turning in one direction, a drum loosely mounted on said sleeve, a coiled spring arranged in said drum and attached at one end to the drum and at its other end to the sleeve, and intermediate gearing connecting the said drum and delivery-roll, whereby when the music-sheet is unwound from the delivery-roll the spring is wound up and operates when the music-sheet is released to rewind it on the delivery-roll, substantially as described.

3. In a rewinding device for music-roll holders for self-playing instruments, the combination with a delivery-roll, of a sleeve loosely journaled on a support and having fixed thereon a ratchet-wheel, a pawl engaging said ratchet-wheel and operating to prevent the sleeve from turning in one direction, a drum loosely mounted on the sleeve and toothed upon its periphery, a coiled spring arranged in said drum and attached at one end to the drum and at its other end to the sleeve, a shaft arranged parallel to the axis of the drum and provided with a gear-wheel meshing with the toothed periphery of the drum, and a train of gearing arranged to transmit motion between said shaft and the delivery-roll, substantially as described and for the purpose specified.

4. In a music-roll holder for self-playing instruments, the combination with a frame carrying a delivery-roll and a take-up roll, and rewinding mechanism for rewinding the music-sheet from the take-up roll onto the delivery-roll, of a cap carried by said frame and fixed opposite one end of the take-up roll, and brake-shoes pivoted to the end of the take-up roll and arranged to be thrown outward against the rim of said cap by centrifugal force and retard the rotation of the take-up roll during the rewinding operation, substantially as described.

5. In a music-roll holder for self-playing instruments, the combination with a movable frame carrying a delivery-roll and a take-up roll and rewinding mechanism for rewinding the music-sheet from the take-up roll onto the delivery-roll, of a cap fixed opposite one end of the take-up roll, brake-shoes pivoted to the ends of the take-up roll and arranged to be thrown outward by centrifugal force against the rim of the cap and retard the rotation of the take-up roll during the rewinding operation, and springs for normally holding said brake-shoes out of contact with said cap, substantially as described.

6. In a music-roll holder for self-playing

instruments, the combination with a movable frame, a delivery-roll and a take-up roll carried by said frame, mechanism for rotating the take-up roll to wind the music-sheet thereon from off the delivery-roll, means for automatically throwing the take-up roll out of gear with the driving mechanism when the end of the music-sheet is reached, rewinding mechanism for rewinding the music-sheet onto the delivery-roll when the take-up roll is thrown out of operation, and means partly carried by the take-up roll and partly by the movable member of the music-holder for retarding the rotation of the said take-up roll during the rewinding operation, substantially as described.

7. In a music-roll holder for self-playing instruments, the combination with a movable frame carrying a delivery-roll and a take-up roll, of mechanism for rotating the take-up roll to wind the music-sheet thereon from off the delivery-roll, means for throwing the take-up roll out of gear with its driving mechanism, means for rewinding the music-sheet onto the delivery-roll when the take-up roll is thrown out of operation, and means partly carried by the take-up roll and partly by the movable frame for retarding the rotation of said take-up roll during the rewinding operation, substantially as described.

8. In a sheet-roll holder for electrical self-playing instruments, the combination with the contact-roller and means for feeding the sheet thereover, of a bar carrying a plurality of contacts or brushes adapted to contact with the contact-roller, a switch-rail, and conductors each connected at one end with one of the brushes and at its other end looped about the switch-rail and projecting beyond the edge of the latter to form a bare contact, said switch-rail and contact-carrying bar, together with the conductors attached thereto, being removably secured to the frame of the said roll-holder, substantially as described.

9. In a sheet-roll holder for electrical self-playing instruments, the combination with the contact-roller and means for feeding the sheet thereover, of a bar carrying a plurality of contacts or brushes adapted to contact with the contact-roller, a perforated switch-rail, a plurality of wire conductors connected respectively at one end to said contacts or brushes and at their other ends threaded through and looped about said switch-rail to form contacts, substantially as described.

10. In a music-roll holder for electrical self-playing instruments, the combination with the contact-roller and means for feeding the music-sheet thereover, of a plurality of brushes or contacts adapted to contact at their free ends with said contact-roller, and a yielding guard-rail arranged to normally lie over and project in front of the free ends of said brushes or contacts, substantially as described.

11. In a music-roll holder for electrical self-playing instruments, the combination with

the contact-roller and means for feeding the music - sheet thereover, of a plurality of brushes or contacts adapted to contact at their free ends with said contact-roller, and a yielding guard-rail arranged to normally lie against the free ends of the brushes or contacts and provided with a depending flange arranged to normally project in front of and below the said free ends of the brushes or contacts, substantially as described and for the purpose specified.

12. In a music-roll holder for electrical self-playing instruments, the combination with a contact-roller and means for feeding the music-sheet thereover, of a plurality of brushes or contacts adapted to contact at their free ends with said contact-roller, means for raising and lowering said contact-roller into and out of engagement with said brushes or contacts, and a yielding guard-rail arranged to normally lie over and against the free ends of the brushes or contacts but yielding and moving away from them when the contact-roller is thrown into engagement therewith, substantially as described.

13. In a music-roll holder for electrical self-playing instruments, the combination with the contact-roller and means for feeding the music - sheet thereover, of a plurality of brushes or contacts adapted to contact at their free ends with said contact-roller, means for raising and lowering said contact-roller into and out of engagement with said brushes or contacts, and the guard-rail supported at its opposite ends on springs and arranged to normally lie over and against the free ends of the brushes or contacts, but yielding and moving away from them when the contact-roller is thrown into engagement therewith, substantially as described.

14. In a music-roll holder for electrical self-playing instruments, the combination with the contact-roller and means for feeding the music - sheet thereover, of a plurality of brushes or contacts adapted to contact at their free ends with said contact-roller, means for raising and lowering said contact-roller into and out of engagement with said brushes or contacts, a guard-rail and springs each attached at one end to the music-roll-holder frame, and attached at their other ends to the opposite end of the guard-rail by screws, said guard normally lying over and against the ends of the brushes or contacts but yielding and moving away therefrom when the contact-roller frame strikes said screws in the act of engaging the brushes or contacts, substantially as described.

15. In an electrical self-playing instrument, the combination with electrically-operated mechanism for actuating the keys and an electrical motor for driving said mechanism, of a music-sheet-feeding mechanism for controlling the key-actuating mechanism, two reversely-arranged cone-pulleys and intermediate belt connections driven by the electric motor for operating the music-sheet-feeding

mechanism, a pivoted switch-lever for throwing the motor into and out of circuit, and a belt-shifter mounted on one end of and movable with the switch-lever and operated by the latter to shift the belt on the cone-pulleys and regulate the speed of the music-sheet-feeding mechanism, substantially as described.

16. In an electrical self-playing instrument, the combination with a base-plate carrying a plurality of electrical contacts or brushes, of a music-sheet-roll holder hinged to the base-plate and carrying a contact-roller adapted to contact with said contacts or brushes and mechanism for feeding the music-sheet over said roller, electrically-operated mechanism controlled by said music-sheet for actuating the key-operating mechanism, and a circuit-breaker operating, when the said hinged music-sheet-roll holder is swung down from normal position, to break the circuit controlling the said electrically - operated mechanism, substantially as described.

17. In an electrical self-playing instrument, the combination with a base-plate carrying a plurality of electrical contacts or brushes, of a music-sheet-roll holder hinged to the base-plate and carrying a contact-roller adapted to make electrical contact with said contacts or brushes, mechanism for feeding the music-sheet over said roller, electrically-operated mechanism controlled by said music-sheet for actuating the key-operating mechanism, two spring-contacts carried by said base-plate and insulated from each other and forming the terminals of the electric circuit for the said operating mechanism, and a metallic projection carried by said hinged roll-holder and operating, when the latter is in operative position to close the circuit between said spring-contacts, substantially as described.

18. In an electrical self-playing instrument, the combination with a music - sheet - roll holder normally operating to move out of operative position when released, mechanism for retaining said roll-holder in operative position, and electrically-operated mechanism for releasing the roll-holder to permit it to drop from its operative position, of an electrically-operated action controlled by said music-sheet for actuating the keys of the instrument, and a circuit - breaker operating when the roll-holder is dropped to throw the said electrically-operated action out of operation, substantially as described.

19. In an electrical self-playing instrument, the combination with electrically-operated mechanism for actuating the keys of the instrument, of electromagnets fixed upon a support, and their armatures, for controlling said mechanism, each of said electromagnets comprising a U-shaped core having its ends inserted or passed through suitable perforations formed in said support, and soldered to the latter, and the helices arranged over the free ends of the core upon the side of the support opposite the bend in the core, substantially as described.

20. In an electrical self-playing instrument, the combination with the electrically-operated mechanism for actuating the keys of the instrument, of a perforated supporting bar or rail, electromagnets supported thereon for controlling the said mechanism, each of said electromagnets comprising a U-shaped core having its ends passed through two of the said perforations in the supporting bar or rail, and having its helices fixed on the ends of the said core on the side of the supporting bar or rail opposite to the bend in the core, substantially as described.

21. In an electrical self-playing instrument, the combination with electrically-operated mechanism for actuating the keys of the instrument, of electromagnets and their armatures for controlling said mechanism, supports for said armatures, each consisting of a flat spring adjustably fixed at one end to a support and bent at the other end at a right angle to lie opposite the core of the electromagnet, the armature being fixed to the free end of said spring, substantially as described.

22. In an electrical self-playing instrument, the combination with electrically-operated mechanism for actuating the keys of instrument, of electromagnets and their armatures for controlling said mechanism, supports for said armatures, each consisting of a flat spring provided at one end with an elongated slot, and a screw passed through said slot and screwed into a fixed support for adjustably supporting said spring, the free end of the spring being bent at a right angle to its fixed end and lying opposite the end of the core of the magnet, the armature being fixed to said free end, substantially as described.

23. In an electrical self-playing instrument, the combination with electrically-operated mechanism for actuating the keys of the instrument, of electromagnets and their armatures for controlling said mechanism, and supports for said armatures, each consisting of a flat spring adjustably fixed at one end to a support and bent at its other end at a right angle to lie opposite the core of the electromagnet and having the armature fixed to said bent end, the fixed end of said spring being provided at its opposite edges with upturned flanges to add strength and stiffness to the spring, substantially as described.

24. The combination with a plurality of contacts or brushes, of a roller movable to and from said brushes on one side, and a guard-rail movable to and from the brushes on the other side, said guard-rail being moved away from the brushes by the roller when the latter is brought into contact with said brushes, substantially as described.

25. The combination with a plurality of contacts or brushes, of a movable guard-rail arranged to bear on one side of the brushes, a movable contact-roller arranged to bear on the opposite side of the brushes, and means for moving the guard-rail away from the brushes when the contact-roller is moved into

contact with said brushes, substantially as described.

26. In an electrical self-playing instrument, the combination with a music-sheet-roll holder normally acting to move out of operative position when released, mechanism for retaining said roll-holder in operative position, and means for releasing the roll-holder to permit it to move from its operative position, of an electrically-operated action controlled by a music-sheet for actuating the self-playing instrument, and a circuit-breaker operating when the roll-holder is moved out of operative position to throw the said electrically-operated action out of operation.

27. In an electrical self-playing instrument, the combination with a plurality of contacts, of a music-roll holder movable to and from said contacts and carrying a contact-roller adapted to contact with said contacts, and mechanism for feeding the music-sheet over said roller, electrically-operated mechanism controlled by said music-sheet for actuating the key-operating mechanism, and a circuit-breaker operating when the music-roll holder is moved out of operative position to break the circuit controlling the said electrically-operated mechanism.

28. In an electrical self-playing instrument, the combination with a music-sheet-roll holder arranged to move out of operative position, mechanism for retaining said roll-holder in operative position, and electrically-operated mechanism for releasing the roll-holder to permit it to move out of its operative position, of an electrically-operated action controlled by said music-sheet for actuating the keys of the instrument, and a circuit-breaker operating when the roll-holder is moved from its operative position to throw the said electrically-operated action out of operation.

29. In a rewinding device for music-rolls, the combination with a delivery-roll, of a sleeve journaled on a support and freely rotatable in one direction, means for holding said sleeve against movement in the opposite direction, a drum loosely mounted on said sleeve, a coiled spring arranged in said drum and attached at one end to the drum and at its other end to the sleeve, and intermediate gearing connecting said drum and delivery-roll, whereby when the music-sheet is unwound from the delivery-roll the spring is wound up and operates when the music-sheet is released to rewind it on the delivery-roll.

30. In a mechanical musical instrument, the combination of a tracker-range, a traveling web mounted on rollers, a frame on which said rollers are journaled, means for unwinding said web, a spring-impelled rewinding mechanism for said web, and a brake device adapted to retard a carrying-roll of said web and automatically controlled by the rewinding mechanism.

31. In a self-playing musical instrument, the combination with a rotary drum, of a plurality of friction-shoes arranged adjacent to

said drum, and adapted to be brought into contact therewith, means operated by said shoes for actuating the keys of a musical instrument, a perforated music-sheet for controlling the action of the shoes, a motor for rotating the drum and for advancing the music-sheet, means for regulating the speed of rotation of the drum whereby the action of the shoes and the force of the stroke of the 10 keys may be varied, and independent means

for controlling the speed of travel of the music-sheet.

In testimony whereof I have hereunto set my hand in presence of two subscribing witnesses.

G. HOWLETT DAVIS.
